UNITED STATES PATENT OFFICE.

EDWARD L. WILSON AND JOHN J. REILLY, OF JERSEY CITY, NEW JERSEY.

FASTENING FOR SHIPPING-TAGS.

1,125,618.

Specification of Letters Patent. Patented Jan. 19, 1915.

Application filed December 17, 1913. Serial No. 807,207.

To all whom it may concern:

Be it known that we, EDWARD L. WILSON and JOHN J. REILLY, citizens of the United States, and residents of Jersey City, in the county of Hudson and State of New Jersey, have invented a new and Improved Fastening for Shipping-Tags, of which the following is a full, clear, and exact description.

10 This invention relates to an improved fastening device for shipping tags, and more particularly to a device to be employed with various commodities which are put up in bales, such as cotton, hay, cloth 15 and the like.

At the present time it is common to cover two sides of a bale with burlap, around which the usual bands or ties are fastened, the burlap serving simply for the purpose 20 of marking thereon with ink, directions concerning the name of the shipper and an appropriate mark or name designating the point of destination and the person to whom the goods are shipped. The burlap is 25 not intended as a protection, and in fact very readily becomes torn or so mutilated that it is impossible to read the marking thereon, words or various characters often 30 being used for this purpose. The result is that the bales will lie at the depot or other point in transit unidentified and without any means to trace their point of destination. Furthermore, since a bale which is 35 compressed to any extent will expand considerably when opened, it is obviously inappropriate to embed any of the identifying parts within the bale, especially if there is any quantity of goods which must be shipped to a farther distant point.

40 The object of the present invention is to overcome the above objections by providing an improved fastening device which consists of extending wires or rods through the bale while the latter is being 45 pressed, so that the ends of these wires will project from the faces of the bale in single or in pairs, for the novel attachment of tags which are preferably of such indestructible material as tin, and which are marked to 50 identify the goods. Furthermore, the tags are mounted on both sides of the bale so that the goods can be more readily identified, as well as provide a more secure anchor for the tags, and it is unnecessary 55 to provide any burlap, as above stated.

With the above and other objects in

view, the invention resides more particularly in the peculiar combinations and arrangements of parts which will be illustrated as a preferred embodiment in the 60 accompanying drawings and described in the specification.

Reference is to be had to the accompanying drawings forming a part of this specification, in which similar characters of 65 reference indicate corresponding parts in all the views, and in which—

Figure 1 is a perspective view of a bale held in compact form with bands and provided with tags secured thereto in accordance with our invention; Fig. 2 is a vertical sectional view thereof; Fig. 3 is a fragmentary sectional view showing a modified form of attaching means; Fig. 4 is a similar view showing a further modified form 75 of attaching means; and Fig. 5 is a plan view of the tag.

As shown in the drawings, a bale is indicated by the numeral 10, the same being of any suitable material to be shipped and 80 held in compact form by ties or bands 11. The tags are indicated by the numeral 12 and consist of strips of non-combustible and non-destructible material such as tin 85 suitably indented with a shipper's mark 13 and having apertures 14 at one or both ends, as shown in Figs. 1 and 2, and 3 and 4, respectively. A blank space is also provided as at 15 for the purpose of inserting the 90 shipper's name.

In the form of the fastening means shown in Figs. 1 and 2, a single rod or wire 16 of resilient material is passed through the bale by inserting the same through the bail 95 ing box during the compressing of the bale, at any convenient point between the ends, so that the ends of the wire project beyond the faces of the bale. The wires then pass through an aperture or eyelet 14, as shown at 17, and are then rebent outwardly and 100 downwardly against the face of the tag, as shown at 18, so as to hold the latter against the face of the bale and prevent the same from contacting with and catching in obstructions. The tags are disposed on 105 both sides and are readily visible from either. The tags are also held from displacement by the pressure against the wires or rods, and the rebent end portions also assist in this purpose.

In Fig. 3 of the drawings a pair of wires or rods 19 are extended through the bale

horizontally of the compressing direction and the projecting ends thereof are passed through the apertures in the tag and then extended toward each other at the centers 5 of the tags and twined about each other, as shown at 20. By twining the ends around each other or connecting the same in this manner the projecting ends are drawn against the faces of the tags so as to hold 10 the latter snug or tight against the faces of the bale to further the object mentioned in connection with the form illustrated in Figs. 1 and 2.

In Fig. 4 of the drawings, the wires are 15 shown spaced apart greater than the lengths of the tags, the projecting ends being extended toward the ends of the tag, as shown at 21, and secured through the apertures thereof, as shown at 22, and in this manner 20 also hold the tags against the faces of the bale. Thus it will be seen that the tags with two apertures may be adapted for attachment to bales with wires which are spaced apart less than the lengths of the tags or 25 at a greater distance than the lengths of the tags; and owing to the fact that the tags are held snug against the faces of the bale, their accidental removal will be obviated, so that the bales can be identified readily at any 30 time during transit.

By reason of the wires being embedded in the bales as above described and the tags attached thereto in the manner specified, the tags are rendered interchangeable without 35 changing the wires and this is especially advantageous where the bales are re-shipped as is commonly done.

Having thus described our invention, we

claim as new and desire to secure by Letters Patent:

1. The combination with a bale; of a tagging device therefor adapted for use during shipment, said tagging device embodying a fastening member extending through the bale at right angles to opposed faces thereof, and tags mounted on the ends of said fastening member outwardly of the bale and bearing shipment data on their exposed faces, said fastening member being bent to engage the exposed faces of the tags to hold 50 the tags in contact with the faces of the bale.

2. The combination with a bale or the like; of a tag fastening device, said tag fastening device embodying spaced rectilinear 55 securing members passed transversely through the bale and having projecting ends, and non-combustible and indestructible tags each having a pair of apertures through which the corresponding ends of 60 the securing members are passed at either side of the bale, said tags being stamped with similar records and the ends of the securing members extended through the apertures being anchored by bending the 65 same to cause the tags to lie flat against the faces of the bale.

In testimony whereof we have signed our names to this specification in the presence of two subscribing witnesses.

EDWARD L. WILSON.
JOHN J. REILLY.
